UNITED STATES PATENT OFFICE.

JOSEPH DYSON, JR., OF CLEVELAND, OHIO; JOSEPH DYSON ADMINISTRATOR
OF SAID JOSEPH DYSON, JR., DECEASED.

APPARATUS FOR FORGING HAMMERS.

SPECIFICATION forming part of Letters Patent No. 507,892, dated October 31, 1893.

Application filed May 27, 1893. Serial No. 475,667. (No model.)

To all whom it may concern:

Be it known that I, JOSEPH DYSON, Jr., a citizen of the United States, residing at Cleveland, in the county of Cuyahoga and State of Ohio, have invented certain new and useful Improvements in Apparatus for Forging Hammers; and I do hereby declare the following to be a full, clear, and exact description of the invention, such as will enable others skilled in the art to which it appertains to make and use the same.

My invention relates to improvements in forging hammers and similar articles and to apparatus therefor; its object is to improve the quality of the articles produced, to insure uniformity of product, and to economize labor; and it consists in the novel method of procedure and novel apparatus adapted thereto, as hereinafter described and pointed out in the claims.

In the drawings Figure 1 represents in front elevation the gang of dies keyed in their die-blocks and placed together in the position they occupy when closed together in working. Fig. 2 is a similar view showing the dies slightly separated. Fig. 3 is a plan view showing the face of the dies in the upper block A. Fig. 4 is a like view showing the face of the dies in the lower block B. Fig. 5 is a series of transverse sectional views centrally through each of the dies and their die-blocks, the upper line showing the sections of the upper dies, and the lower line the sections of the lower dies, in the same order as they appear in Figs. 1 to 4. Fig. 6 represents the forging in its various stages from the rod to the finished blank, the suffixed letters indicating the pair of dies by which each stage was produced. Figs. 7 and 8 exhibit the finished hammer in side and front view respectively.

In the manufacture of hammers and other articles the superiority of hand forged articles over those made by drop-forging and swaging has long been well understood and universally conceded. One of the chief reasons for this superiority is that hand forging is done at much lower temperature than is practicable with machine forging, since in the latter case, and especially in drop-forging or swaging, the metal must fill the form into

which it is to be forged suddenly under the impact of the heavy blow to which it is subjected, and to avoid cracking, the metal must be so highly heated as to flow readily and quickly under the heavy blow of the drop hammer, and a high heat is also necessary to enable the die or form to be accurately filled by the metal when it is struck. 55

It is an axiom in metal working that the less heating the metal is subjected to in the process of manufacture the better is the quality of the product, and this applies with especial force to steel, as it is well known that it is very liable to change its nature when highly heated, or if heated too often. 60

For the above and other well understood reasons it is nearly impracticable to produce by drop-forging articles of steel in which the qualities of great strength and hardness are essential, since the quick flow of the metal gives rise to lamination and lines of molecular strain, and the high heat causes the steel to change its nature more or less. In the case of steel hammers and similar articles 70 these defects become very apparent when they are made by drop-forging, as the hammers, when subjected to the usage for which, they are intended, are very liable to crack along the lines of internal molecular strain, 75 and soon break and become worthless. In hand-forging, on the contrary, the metal being at a lower heat preserves its nature, and as the blows upon it are numerous and, by comparison, light, the flow of the metal is slow, lamination is prevented, and the molecular structure is undisturbed, so that the lines of internal strain are wholly absent, and the metal remains as homogeneous as it was before forging. 80 90

Owing to the great expense involved in forging articles by hand, efforts have been made to accomplish by means of power hammers and swaging the desirable results of hand forging with less labor, the practice being usually to first drop-forgue the blanks and then re-heat and swage the blanks in suitable dies, but so far as I am aware the results of all such efforts have proven unsatisfactory and they have been abandoned for most articles, and entirely so for hammers, as the metal in swaging has not the necessary freedom of 95 100

molecular flow which it has in hand forging, and which is necessary to the production of satisfactory forgings. To accomplish by means of power hammers the same results obtained by hand forging is the aim of my invention, and I accomplish this by the means and in the manner presently to be described, thereby enormously reducing the amount of labor, and consequently the cost of the product.

To apply my invention I construct a series of dies having the necessary form and characteristics, hereinafter described, and adapted to progressively shape the article from the bar to the finished blank, ready for grinding, such series of dies forming what is called a "gang" of dies, and each set or gang of dies for a single article being arranged in a die-block and securely fastened therein, while the die-block is secured to the head of a suitable power hammer in the usual way, the set of counter dies being arranged in proper order in a similar die-block secured in the proper position on the bed or anvil block of the hammer.

Referring to the drawings, A represents the upper die-block, B the lower one, a, b, c, d, e, the upper dies, a', b', c', d', e', the corresponding lower dies of each pair.

f f represent stops or gage blocks, technically known as "kiss-pieces," which are inserted at each end of the gang of dies in each block, and g g are keys or wedges by which the dies and kiss-pieces are firmly fastened into their die-blocks. As the attachment of the die-blocks to the head and anvil of the hammer does not differ from the usual method of attaching dies to a power hammer, it is not shown in the drawings, the construction and arrangement of the dies themselves embracing the features of novelty.

The die-blocks A and B are alike, and are each provided with a dovetail recess k, open at one end of the block for insertion of the dies. The dies and kiss-pieces are each formed with a dovetail base fitting the recess k, as seen in the cross-sections, Fig. 5. The kiss-pieces f f are formed with flat faces, and are of such a height that when they "kiss" or meet together the dies will have fully formed the metal between them to the extent they are designed to. By this means the wearing of the dies is prevented, exact uniformity of product is secured, and undue strain upon the dies is prevented. As the dies and kiss-pieces are readily removable from their die-blocks, any of them may be removed and quickly replaced by other or different ones as the varying character of the work requires, and thus a few dies answer for a large range of work.

The dies are described, in the order in which they act, as follows:

a a' are the "necking" dies, or first pair, and are alike, each having the central nearly hemispherical space a² and the projecting nearly semi-circular ribs a³ a⁴, of which a³ is

preferably of larger radius than a⁴ and forms the larger neck l, when forging a hammer.

b b' are the "flattening" dies, or hammer faced flat dies by which the blank is flattened, squared, or trued up as may be required.

c c' are the piercing dies, c being provided with the piercing point or punch c² which forms an eye through the metal, and c' having a central globose cavity c³ and the oppositely disposed curved horns c⁴ c⁵, of which c⁴ is the longer and more curved and is placed on the front side of the die, toward the operator.

d d' are reducing dies, by which the diameter of the rod is reduced and a ball peen roughed out. These dies are similar and each has the necking edge d² and approximately cylindrical shoulder d³ for reducing the rod 85 and forming the small end of the hammer.

e e' are the cutting-off dies, e having the cutting edge e², and e' having the shallow, concave recess e³, into which the end of the rod or bar is laid while cutting-off, and the 90 end of which recess forms a stop or gage to insure the accurate placing of the rod or bar in cutting off the blank when the forging is complete.

The operation is as follows: In forging hammers of the pattern shown in Figs. 7 and 8, a round bar of steel with flat end, (such as is shown at 6 e after cutting off,) is heated in a convenient furnace to a merely red heat at the end, as it would be in hand forging; it is then placed in the first die a', and given several blows of the hammer, meanwhile being turned over, until the pieces f f "kiss," when the rod will have reached the shape shown by 5 a, and will have had the 105 large head L, the two necks l m, and the central globose swell N, completely formed. In this operation the metal forming the head L, being entirely free, is practically left unchanged, and the metal which is displaced to 110 form the necks l m is forged toward the center, causing the metal in the center to swell into the globose form shown at 6 a by slow molecular flow without strain. The blank thus forged in the dies a a' is next placed on 115 b' and given one or more blows of the die b, whereby the globose central part N is flattened on two or more sides as desired, giving it the flat face n seen in Fig. 7, and leaving the rod or blank of the form seen at 6 b. The 120 blank is not placed in the die c' by inserting it diagonally between the ends of the horns c⁴ c⁵ and then turning it square across the die, which brings the neck l against the horn c⁵, and the neck m under the horn c⁴, and thus 125 an extremely firm bearing for the blank is obtained, which prevents it from turning or moving when the die c is struck upon it, the punch c² striking the blank centrally and punching it nearly through. The horn c⁴ holds the blank when the die c lifts, whereby the punch c² is withdrawn without either straining the punch or distorting the blank.

When the upper die c lifts clear of the blank

the latter is turned over and a second blow of the die *c* punches the hole clear through, leaving it a little larger at each end than at the middle, which is desirable for the purpose of firmly securing the handle to it. The blank has now the shape shown in 6 *c*, and the rod is placed upon the die *d'* and, being turned over between the blows struck by the die *d*, is reduced in diameter at the portion next to the neck *m*, and at the same time is necked down between such reduced portion and the remainder of the rod, assuming by the time the pieces *f f* "kiss," the shape shown in 6 *d*, and having the small head *M* and the ball peen *o* completely roughed out. The last operation is to place the blank on the die *e'*, the body of the rod resting in the shallow recess *e*³ with the end of the rod butted against the end of the recess, when the cutting edge *e*² of the die *e* will serve the small neck of metal between the rod and the peen *o*, leaving the rod flat-ended and ready to be heated again, and the finished blank cut free and ready for grinding, as shown at 6 *e*. Obviously a hammer with a square head in place of the cylindrical head *L* would have been produced by using a square bar instead of a cylindrical rod.

I am aware that dies have been used in the forging of hammers, chiefly for claw hammers, but heretofore it has been necessary to first cut the blank from the bar and afterward shape the separate blanks in the dies, which involve the repeated heating of the blanks, which I avoid by forging directly from the bar at a single heat, leaving the completed forging to require only the customary grinding and polishing to completely finish it.

What I claim as my invention, and desire to secure by Letters Patent, is—

1. The combination in hammer forging apparatus of a die-block adapted to be secured to a hammer head or anvil block and having a die-receiving recess of a length to receive all the dies of a gang, a series of interchangeable dies fitting in said recess and comprising a necking die, a flatting die, a piercing die, a reducing die and a cutting-off die, a kiss-piece to limit the action of the dies, and a key passing through the die-block transversely to the die recess to lock the dies therein, all constructed and combined substantially as described.

2. The combination in hammer forging apparatus of a gang of dies comprising a neck-

ing die, a flatting die, a piercing die, a reducing die and a cutting-off die, all secured in a single die-block with a kiss piece or pieces to limit the action of the dies, with a corresponding gang of counter dies comprising a necking die, a flatting die, a holding die, a reducing die and a gage or guiding die, all secured in a single die-block and opposed to their corresponding dies in the other gang, substantially as described.

3. The necking die for forging hammers, having on each side a projecting rib with a central curved depression, for simultaneously forming the two necks of the hammer without compressing the metal outside of the necks, substantially as described.

4. In combination with a piercing die the holding die having the concave center and the oppositely disposed curved horns integral with the body of the die, for guiding and holding the blank while being pierced, substantially as described.

5. In combination with a cutting-off die the gage-die having a semi-cylindrical groove terminating in a vertical face in line with the cutting edge of the cutting-off die, for guiding the blank to prevent distortion of the same in cutting off, substantially as described.

6. The combination in hammer forging apparatus of the pair of necking dies each having a concave center and on each side thereof a projecting rib with a central curved depression, the pair of flatting dies, the pair of piercing dies, having on the upper one the piercing point and on the lower one the oppositely disposed curved retaining horns, the pair of reducing dies each having a projecting rib with a semi-cylindrical depression therein terminating in a necking edge, the pair of cutting off dies, of which the upper has a cutting edge and the lower has a guiding groove terminating in line with the cutting edge of the upper die, and the pair of kiss-pieces to limit the action of the dies, the dies being arranged in an upper and lower gang each containing one die of each pair arranged opposite its fellow in the other gang, substantially as described and for the purpose set forth.

In testimony whereof I hereto affix my signature in presence of two witnesses.

JOSEPH DYSON, JR.

Corrections in Letters Patent No. 507,892.

It is hereby certified that in Letters Patent No. 507,892, granted October 31, 1893, upon the application of Joseph Dyson, jr., of Cleveland, Ohio, for an improvement in "Apparatus for Forging Hammers," errors appear in the printed specification requiring correction, as follows: In line 105, page 2, the reference letter "5^a" should read 6^a; in line 121, same page, the word "not" should read *next*, and in line 20, page 3, the word "serve" should read *sever*; and that the Letters Patent should be read with these corrections therein that the same may conform to the record of the case in the Patent Office.

Signed, countersigned, and sealed this 7th day of November, A. D. 1893.

[SEAL]

JNO. M. REYNOLDS,
Assistant Secretary of the Interior.

Countersigned:

JOHN S. SEYMOUR.
Commissioner of Patents.
